UNITED STATES PATENT OFFICE.

JAMES DANIEL MCKINNON, OF PORTLAND, OREGON.

COMBINED HARROW, ROLLER, &c.

SPECIFICATION forming part of Letters Patent No. 289,118, dated November 27, 1883.

Application filed May 21, 1883. (No model.)

To all whom it may concern:

Be it known that I, JAMES D. MCKINNON, of Portland, in the county of Multnomah and State of Oregon, have invented a new and Improved Combined Harrow, Roller, Seeder, and Cultivator, of which the following is a full, clear, and exact description.

The invention will first be described in connection with the drawings, and then pointed out in the claims.

Reference is to be had to the accompanying drawings, forming part of this specification, in which similar letters of reference indicate corresponding parts in all the figures.

15 Figure 1 is a side elevation of my improved machine. Fig. 2 is a front elevation of one side with some of the parts in section. Fig. 3 is a detail sectional view of the rim of one of the wheels and a portion of the rim of the drum, and Fig. 4 is a detail sectional view of the harrow-cylinder.

I make wheel-rims *a* for the truck-wheels, having a groove, *b*, in one side, in which the end of the roller shell or drum *c* is made to fit, 25 for connecting the drum when it is to be used for rolling the ground, the connection being such that the said drum *c* can be detached from the wheels *a* when it is not required for use, the wheels then forming simply a truck.

30 The outer side of each wheel-rim *a* has a rim, *e*, of smaller diameter than the rim *a*, and provided with spurs *f*, for driving an endless chain, *g*, for rotating the harrow-cylinder *h*, the said rims *a e* having spokes *i*, for being connected to an axle, *j*, by a hub thereon, 35 which axle is mounted in boxes *k* of the frame *l*. The boxes *k* are bolted to the frame *l*, so that they can be taken off readily to allow the wheels, or one of them, to be shifted along the

40 axle a little, for allowing the drum or shell *c* to be connected to the wheels for use in rolling the ground, or disconnected when the wheels are to be used without the drum to work the harrow and seeder only. The boxes *k* have a hub, *m*, extending each side of them, to support the radius-bars *n*, in which the harrow-cylinder *h* is mounted, said bars *n* being divided or forked, to connect with said hubs *m* each side of the boxes *k*, and being connected there-

45 by yoke-straps *o*, fitted around the hubs and bolted to the bars.

By connecting the bars *n* to the hubs *m* instead of the axle *j*, a considerable amount of friction is avoided that would be caused by the pressure of the bars on the journals of the 55 axle *j*.

The harrow-cylinder *h* has teeth *p*, which, as represented in the drawings, consist of metal bars having points *q*, which are bent upward or backward with reference to the direction 60 in which the harrow revolves, the object of which is that they shall beat the clods downward and cut and pulverize them to better advantage than if they were straight. The teeth *p* are also set with an angle to form a 65 cutting-edge for more effective operation than if turned flatwise to the direction in which they revolve. Said teeth are screwed into the cylinder *h*, and have check-nuts *s*, which screw against the surface of the cylinder *h*, to bind 70 them fast, and for a means for readily detaching them to change from one form of teeth to another for different kinds of work. For instance, to cultivate corn, I propose to substitute teeth having share-points and mold-boards 75 contrived to turn the earth sidewise, for turning the soil up to and around the roots of the corn, and will arrange such teeth in rows around the cylinder suitably for working each side of the rows of corn and turning the earth 80 up to both sides of the corn, having two or three sets of the teeth for two or more rows of corn, according to the length of the harrow-cylinder and the truck-axle. When cultivating corn, the roller-shell *c* will be detached 85 from the wheels.

The harrow-cylinder *h* may consist of a wood roller or a hollow metal shell, as preferred, but will have caps *t* for the ends, which connect by screwing onto said ends, as represented 90 in Fig. 4, the said caps *t* having a journal, *u*, by which the cylinder is mounted in the boxes *v* of the radius-bars *n*. The caps *t* also serve for the chain-pulleys on which the driving-chains run, having spurs *f* cast on them to 95 connect with the chain. These bars *n* are suspended by a chain, *w*, passing over guide-pulleys *x* to the shaft *y*, by which said chain is wound up or let out to raise or lower the harrow to regulate it with reference to the depth 100 the teeth are to work and for suspending the harrow above the ground, the said shaft being

mounted in suitable bearings, *z*, on the frame, and having a crank, *a'*, for turning it, and a ratchet and pawl, *b'*, for holding said shaft to set the harrow.

5 Over the harrow I have arranged a seed-hopper, *c'*, in which a rotary seed-dropper of any approved kind is to be arranged, which I propose to gear by means of a chain-pulley, *d'*, having spurs *f*, like those of the rim *e*, and arranged with such relation to chain *g* that said pulley *d'* will be turned by said chain at the same time that the harrow is turned by it.

I propose to make the frame *l* of angle-iron, for the best material to use for a light, strong, 15 and cheap frame, and will attach seat-supporting standards *f'* over the axle, to the top of which I connect a bar, *g'*, extending from side to side and supporting the seat *h'* in the center of the machine, where the regulating-shaft *y* is located, or in suitable proximity to crank *a'* of said shaft.

The bar *g'* is fitted to the supporting-stands *f'* by turned ends *i'*, projecting through

the holes of the standards and fastened by pins *j'*, to be readily detachable when required. 25

m' represents a chute to be used in connection with the seed-dropper for discharging the seed in advance of the harrow.

Having thus described my invention, I claim as new and desire to secure by Letters Patent— 30

1. The combination, with the drum *c*, of the wheel-rims *a a*, grooved at *b*, and rigidly connected by spokes with a hub on the axle, as described, whereby when the hubs are in place on the axle the drum is held securely 35 between the rims, but when the hubs are moved to the ends of axle the drum may be removed, as set forth.

2. In combination with the roller-frame, the boxes *h*, having a hub on each side, the forked bars *n*, the yoke-straps *o*, and the revolving toothed drum, as shown and described. 40

JAMES DANIEL MCKINNON.
